[57] CLAIM

The ornamental design for a data terminal, as shown and described.

DESCRIPTION

FIG. 1 is an isometric view showing the top, left, and front sides of a data terminal showing our new design;

FIG. 2 is a rear view thereof;

FIG. 3 is a bottom plan view thereof; and,

FIG. 4 is a right side view thereof.

The structures represented by broken lines are intended to show environmental features, and are not part of our claimed design.
